J. W. CALLAHAN.
ADVERTISING MEDIUM.

No. 365,907.

Patented July 5, 1887.

UNITED STATES PATENT OFFICE.

JAMES WEST CALLAHAN, OF NEW IBERIA, LOUISIANA.

ADVERTISING MEDIUM.

SPECIFICATION forming part of Letters Patent No. 365,907, dated July 5, 1887.

Application filed April 8, 1886. Serial No. 198,286. (No model.)

To all whom it may concern:

Be it known that I, JAMES WEST CALLAHAN, a citizen of the United States, and a resident of New Iberia, in the parish of Iberia and State 5 of Louisiana, have invented certain new and useful Improvements in Advertising Mediums, of which the following is a specification.

My invention relates to improvements in advertising mediums, and has for its object 10 the provision of a device of the class named, adapted to be placed in railroad-stations, post-offices, hotels, &c., to indicate the time of arrival and departure of mails or railroad-trains, and to display to view different desired 15 advertisements.

To these ends the invention consists in a case or cabinet having its front provided with a series of apertures to display different words, terms, or characters, printed, stamped, or 20 otherwise fixed, and movably secured to or upon a belt or band suitably mounted within the case.

The invention further consists in means whereby different desired characters may be 25 caused to appear at the same place upon said belt at the will of the operator; and it finally consists in the construction, arrangement, and combination of parts for service, substantially as hereinafter described, and specifically 30 pointed out in the claims.

In the drawings, Figure 1 represents a front elevation of an advertising medium constructed in accordance with my invention. Fig. 2 represents an enlarged rear elevation 35 thereof. Fig. 3 is a side elevation. Fig. 4 represents an enlarged longitudinal section taken on the line $x-x$ of Fig. 2. Fig. 5 is a transverse section taken on the line $y-y$ of Fig. 2. Fig. 6 represents an elevation of the character-bearing belt or band detached from the 40 device. Fig. 7 is a sectional view taken on line $z-z$ of Fig. 6. Fig. 8 is a detached detail view of a modified form of the advertisement-bearing belt or band, and Fig. 9 represents in 45 elevation a modified form of my invention.

Referring to the drawings, in which similar letters of reference denote similar parts, A designates a case or cabinet, which may have any desired configuration of outline, or external 50 ornamentation other than that shown herein, which consists in side rails, a , top and

bottom rails, a' a'' , and front or face a^3 , having apertures, hereinafter described.

B B' designate rollers journaled in the vertical plane in boxes b b' , secured to the rear 55 surface of the front a^3 within and near the opposite sides a of the case, at the upper part thereof, and provided at their lower ends with frictional bevel-wheels b^3 b^3' , that engage and are operated by similar frictional bevel-wheels, 60 c c' , mounted upon the inner ends of short horizontal shafts C C', journaled in and projecting outwardly through suitable boxes, c^2 c^3 , secured in the sides a , to receive removable operating-cranks C² upon their squared outer 65 ends c^4 c^5 , as shown. The bevel-wheels c c' engage and operate frictional bevel-wheels d d' , mounted upon the upper ends of rollers D D', that are journaled in boxes d^2 d^3 , secured to the inner surface of the front a^3 , near the opposite sides of and in the lower part of the case, and provided at their lower ends with small band-wheels d^4 d^5 , connected together by a band or belt, d^6 , for a purpose hereinafter described. 75

E designates a broad band or belt, which may be of suitable textile material or of metal, as desired, that extends from one to the other of the rollers B B', and is provided at spaced intervals with a series of slits, e , that extend 80 in the longitudinal direction of the belt, to receive narrow strips F, of suitable material, that extend and operate transversely of the belt E, and are each provided on its face with numerals from 1 to 9 and 0, for a purpose hereinafter 85 described. I preferably connect the opposite ends of each of the strips F together after said strips are in position in the slits e of the belt E, but do not limit myself to such construction, inasmuch as the ends of said strips 90 may be free from each other without impairing the efficiency of the strip.

G designates an endless belt or band extending between, passing about, and operated by the rollers D D'. This belt may also be made 95 of textile material or of metal, as desired, and is adapted to receive upon its outer surface a series of advertisements, as will be hereinafter fully set forth and described.

While the above-described device is adapted 100 to be used in different desired connections, it is yet more particularly designed for service

in railroad-stations or post-offices, to indicate, in connection with the advertisements, the time of arrival and departure of different trains or mails; and to this end I provide the upper belt, 5 E, upon its outer surface, near its top, with the words "East," "West," "North," "South," and arrange below and above each of said words a series (preferably four transversely-extending rows) of the slits e, having bands 10 F passed therethrough, so as to alternately appear upon the opposite surfaces of the belt E, (see Fig. 6,) whereby any desired numbers upon the strips F may be placed in consecutive order below, and in a parallel plane with said words "East," &c.—as, for instance, the numbers "1, 2:1, 5" read "twelve fifteen"—I provide the front a³ of the case A, in the planes of the words "East," &c., and row of numerals "12:15," with apertures or slots m m', through 15 the upper of which, m, any desired one of said words may appear, while the entire row of numerals appear at the lower, m', of said slots. I provide the front a³ above the slot m with the inscription "Next train (or mail) leaves. 20 25 Going," arranged in the order shown in Fig. 1, and between said slots with the word "at," so that the complete legend sets forth that the "Next train (or mail) leaves, Going East, at 12:15."

30 For the purpose of giving information regarding delayed trains or mails, I provide the front a³, below the slot m', with a section of slate, n, or of wood or paper having surfaces of silicate adapted to be written upon.

35 If desired, the front a³, immediately in front of the lower belt, G, may be entirely cut away, as shown, for the purpose of displaying advertisements arranged upon said belt G below and in alignment with the words "East," &c., 40 upon the belt E.

I preferably show different advertisements in connection with each of said words "East," &c.

If desired, but two rollers may be used in 45 lieu of the four—to wit, B B' and D D', herein described—and may receive motion either at their tops, bottoms, or middles. The belt E may be endless and pass continuously in one direction about the rollers B B', which rollers 50 may have suitable springs applied to their ends for the purpose of maintaining the proper tension of said belt.

If desired, the belt G may be secured at its ends to the rollers D D' and alternately wound 55 upon or unwound from said rollers in manner similar to that of the belt E. When this construction is employed, I preferably use, in lieu of the narrow belt d⁶, a narrow strip, g, of suitable material, placing the same upon the 60 side of the rollers D D' opposite to that occupied by the belt G, and connecting its opposite ends to said rollers, for reasons clearly apparent from the drawings.

If desired, the lower portion of the front 65 a³ may be without slot or opening, and may have any desired advertisement thereon, as shown in Fig. 9.

The operation of my improvement will be understood without further description, it being apparent that the rotation of the shafts C 70 or C' will cause the belts E and G to move either to the right or left, as desired.

Without limiting myself to the precise construction shown and described, I claim—

1. An advertising medium consisting of a 75 case or cabinet having an apertured front, a movable belt within said front provided with fixed legends, movable legend-bearing strips connected to said strips, and means, substantially as described, to operate said belt from the exterior of the case to cause the fixed and movable legends to appear at the aperture in the front, as and for the purpose set forth.

2. In an advertising medium, a case or cabinet having an apertured front provided with 85 fixed legends and slate-section, and two or more rollers journaled in the vertical plane within said case and provided with bevel-wheels, in combination with one or more belts or bands having legends fixed thereto and means, substantially as described, for operating said rollers to move said belts, as and for the purpose 90 set forth.

3. A case or cabinet having an apertured front, and two or more rollers journaled in the 95 vertical plane within said case and provided with bevel-wheels, in combination with one or more shafts journaled in the horizontal plane, and provided with bevel-wheels, and belts or bands mounted on said rollers and laterally 100 operated thereby, substantially as described.

4. In an advertising medium, a belt or band, as E, having a series of longitudinally-extending slits, as e, to receive a series of transversely-extending strips, F, in combination 105 with rollers B B', having bevel-wheels, as b² b³, and shafts C C', having bevel-wheels, as e e', and cranks, as C², substantially as described.

5. The combination, in an advertising medium, of a case or cabinet having an apertured front provided with fixed legends, with a movable belt or band within said case provided with fixed legends, movable legend-bearing strips connected to said belt or band, and means, substantially as described, to adjust said strips upon the belt and to move said belt in lateral direction to cause the legends to appear at said aperture, as and for the purpose specified.

6. In an advertising medium, a belt, as E, having slits, as e, and transversely-extending strips, as F, said belt mounted upon rollers, as B B', in combination with a belt, as G, mounted upon rollers D D', having bevel-wheels d⁴ d⁵, band-wheels d⁴ d⁵, and belt d⁶, and means, substantially as described, to operate said rollers and belts, as and for the purpose described.

7. In an advertising medium, the combination of a case or cabinet having an apertured front, a laterally-moving belt or band having fixed legends, legend-bearing strips movably connected to said belt, and means, substan-

tially as described, to move said belt and its connected strips to cause the legends thereon to appear at the aperture in the front, as and for the purpose set forth.

8. A case or cabinet having an apertured front and a belt or band provided with longitudinal slits *e*, to receive strips *F*, in combination with rollers *B B'*, having bevel-wheels, and means, substantially as described, for operating said rollers to move the belt, as and for the purpose specified.

9. In an advertising medium, a case or cabinet having a front provided with apertures *m* and *m'*, a slate-section, *n*, and fixed legends, in combination with a laterally-moving belt, *E*, having fixed legends, slits *e*, formed in said belt to receive strips *F*, legend-bearing strips *F*, rollers *B* and *B'*, and means, substantially as described, to move said belt to expose dif-

ferent legends at said apertures, as and for the purpose set forth.

10. In an advertising medium, a belt or band, *G*, mounted upon rollers *D D'*, and provided with a series of fixed legends, in combination with a belt, *E*, provided with fixed legends, and slits *e*, to receive legend-bearing strips *F*, said strips *F*, and means, substantially as described, for simultaneously moving said belts *E* and *G*, as and for the purpose specified.

In testimony whereof I have signed my name to this specification in the presence of two subscribing witnesses.

JAMES WEST CALLAHAN.
